UNITED STATES PATENT OFFICE

2,402,017

ADJUSTABLE QUILL

Carl O. Bruestle, Rahway, N. J., assignor to Borg-Warner Corporation, Chicago, Ill., a corporation of Illinois

Application October 25, 1943, Serial No. 507,579

6 Claims. (Cl. 140—36)

1

This invention relates to wire weaving machines and more particularly to an improved wire quill assembly for such machines.

It is an object of this invention to provide a wire quill assembly for a weaving machine, somewhat similar to the wire quill assembly shown in the patent to I. B. Hill No. 2,268,658, issued January 6, 1942, but with certain improvements therein.

It is a further object of this invention to provide a quill which is adjustable axially or longitudinally. In this connection, it has been found that under continuous use, the discharge end, that is, the tying end, of the quill wears down at the ends of the groove or guide means for the warp wire, with the result that the warp wires are not held in the proper position for the tying operation. This results in the screen losing some of the desired optical characteristics due to the fact that the wires will improperly feed from the end of the worm quill and the resulting wire fabric will have an irregular weave therein.

It is an object of this invention to provide a construction in which the quill may be removed from the machine, filed, cut, or ground into the desired form across the end, and then replaced in the machine and properly adjusted longitudinally.

It is an object of this invention to provide a quill construction with a novel clamping means retaining it in any desired position in the machine.

It is likewise an object of this invention to provide a construction in which the quill is adjustable arcuately. In this connection, it is an object to compensate for backlash which may be developed by excessive wear of the gears and parts, so that the guide channels for the warp wires are always in the desired position with respect to the wearing means.

It is another object of this invention to provide a readily releasable holding means which makes it possible to adjust the quill either arcuately or axially or both, as may be desired, and hold the quill in the adjusted position with respect to the pinion.

It is a further object to disclose a construction which is relatively inexpensive, easily manufactured, easily manipulated by use of a small wrench or screw-driver, and which has means securely retaining the device in the adjusted position.

Other objects, the advantages and uses of the invention will become more apparent after reading the following specification and claims, and after consideration of the drawing forming a part of the specification, wherein:

2

Fig. 1 is a longitudinal sectional view of a quill embodying the invention disclosed herein, which quill is indicated as installed in a weaving machine;

5 Fig. 2 is a fragmentary cross-sectional view taken on the line 2—2 of Fig. 1 looking in the direction of the arrows; and

Fig. 3 is a fragmentary perspective view of a portion of the quill, the portion being the discharge end thereof.

Referring more in detail to the construction shown in the various figures, there is provided what may be termed the quill assembly 20. This quill assembly 20 is shown as mounted in the axle 15 bore of a pinion 22, so as to rotate with said pinion 22. The pinion 22 in turn is journaled for rotation as a part of a weaving machine 24, and is driven by the rack 26 in the well-known manner.

20 The weaving machine 24 has the weaving head which includes a back plate 28 and a comb 30, the forward face of the back plate 28 and the adjacent offset portion of the face of the comb 30 defining a guideway 32 for the filler strand or

25 ribbon-like element 34.

The quill assembly proper comprises the quill rod 36, which is drilled and tapped as shown at 38. This drilled portion 38 is flared or chamfered at its outer end as shown at 40, and the quill rod 30 36 is cut longitudinally, preferably to a relative position such as is indicated by the saw cut 42. One or more saw cuts may be made if desired. These saw cuts allow a portion of the quill rod to be expanded as hereinafter described.

35 The adjustment screw 44 threads into the hollowed-out and tapped portion 38. This adjustment screw 44 is provided with an enlarged head 46, which is preferably beveled or shaped like a truncated cone, the head 46 being adapted to

40 engage the chamfered portion 40 of the quill rod 36 as the adjustment screw is threaded into the drilled and tapped portion 38. As the adjustment screw 44 is turned so as to thread it into the portion 38, the head 46 engages the quill rod 45 36 as above explained and forces the quill rod to expand diametrically by spreading the saw cuts somewhat, and this expansion will result in the quill rod 36 engaging the sides of the bore of the pinion 22 with a firm grip, which will hold the

50 quill rod 36 firmly in the position desired within the bore of the pinion 22.

The drilled and tapped portion 38 may be tapered very slightly throughout most or all of its length whereby it will be expanded more uniformly by the adjustment screw 44. Also, the ad-

justment screw 44 may be tapered throughout its length a very slight amount for the same purpose, regardless of whether the drilled and tapped portion 38 is tapered. Preferably, both have a very slight taper, with the adjustment screw having an enlarged head portion as above described.

The adjustment screw 44 at its head portion 46 has a tool-engaging portion 48, by means of which a wrench or other tool may be used to tighten the adjustment screw into position. It may be notched for a screw-driver or provided with a socket, if desired.

The quill rod 36 is provided with the axially extending diametrically opposed grooves or the like 50, which provide the channel means for the warp wires 52.

The pinion 22 is provided with the pinion teeth or leaves 54 for engagement by the teeth 56 of the rack 26.

The operation of the device is as follows:

The quill rod 36 is inserted into the bore of the pinion 22 and is moved to the position desired, which is normally the arcuate position shown in Fig. 2 wherein the warp wires 52 are one above the other in perpendicular alignment with the axis of the quill rod and the longitudinal position shown in Fig. 1, the quill rod having been moved longitudinally until it extends to the predetermined position. It is then held securely in place and the adjustment screw 44 is threaded into the drilled and tapped portion of the quill 38 until it seats against the sides of the drilled portion thereof and expands the quill into engagement with the bore of the pinion 22. The adjustment screw 44 is then firmly tightened into position and the quill assembly will be securely held against movement relative to the pinion 22.

The wires 52 are then threaded into position in the channel 50, and are carried through the weaving head, performing the weaving operation in a manner such as is disclosed in United States Patent No. 2,223,317, issued to Ewing November 26, 1940. The rack 26 engages the leaves 54 of the pinion 22 for rotating said pinion and quill assembly. The wires 52 should be aligned as above suggested, and frequently the wear on the pinion teeth 54 and on the rack teeth 56 allow a small amount of play which may be termed "backlash," which causes the quill to be stopped in its rotation at a position where these wires 52 are not properly aligned with the slits in the comb. This will result in the woven article having irregularities which are objectionable. Accordingly, it is possible to compensate for this wear by adjusting the quill arcuately by turning it to where wires 52 will be in the proper alignment when the teeth of the rack and pinion engage.

It is also possible to compensate for the fact that the grooves 50 frequently wear off as is indicated in Fig. 1 whereby they become rounded and are not properly proportioned or positioned for performing the weaving operation. In any of such cases, the adjustment screw 44 is loosened or removed and the quill is removed from the bore of the pinion. In case the ends have become worn, the quill may be ground off past the worn part so the grooves again will present a square edge with the end of the quill. It may well be noted that for this purpose the quill may have been cut away in manufacture as shown at 58, which leaves less material to be ground away for squaring the ends. After the quill has been repaired, it may be reinserted in the bore and fastened into place by tightening the adjustment

screw 44. In the event the quill needs to be aligned arcuately to compensate for wear of the rack and pinion teeth as above mentioned, this may be accomplished likewise by releasing the adjustment screw 44, setting the quill at the desired arcuate position, and again tightening the adjustment bolt 44, thus locking the quill assembly in the desired position.

With this arrangement, it is also possible to replace the quill easily and quickly.

It will thus be seen that this quill arrangement provides a flexibility of operation and repair which is not present in other devices for the same purpose.

While I have described my invention in connection with certain specific embodiments thereof, it is to be understood that this is by way of illustration rather than limitation and that the invention is to be defined by the appended claims which should be given a scope as broad as commensurate with the prior art.

I claim:

1. As an article of manufacture, a quill comprising in combination means receiving material to be woven, a drilled and tapped end portion, an axial split such as a saw cut in said drilled and tapped end portion, and means operable for axial adjustment of the quill including means for expanding said drilled and tapped end portion.

2. As an article of manufacture, a quill comprising in combination means receiving material to be woven, a drilled and tapped end portion, an axial split such as a saw cut in said drilled and tapped end portion, and means operable for expanding said drilled and tapped end portion, said expanding means comprising an adjustment screw having an enlarged portion.

3. A quill assembly means for a weaving machine and the like comprising a pinion mounted for rotation in said weaving machine, a bore in said pinion, a quill rod removably inserted in the bore of said pinion, an adjustable means releasably retaining said quill rod in the bore of said pinion, said last-mentioned means comprising an expandible hollowed-out portion of said quill rod, and adjustable means in connection with said hollowed-out portion for expanding and holding said quill rod in releasable engagement with said pinion, whereby said quill rod is axially adjustable.

4. In a device of the class described, a quill rod removably mounted in a pinion, said quill rod having an axially extending drilled and tapped portion, a saw cut extending axially at least part way the length of said drilled and tapped portion, means defining an adjustment screw threaded into said drilled and tapped portion, adjustable for expanding said quill rod and thereby holding it in said pinion at a predetermined position, said means likewise being adjustable for returning said quill rod to normal, whereby said quill rod is released from said pinion.

5. In a device of the class described, a quill rod assembly comprising in combination a quill rod, a pinion having an axially extending bore, said quill rod being removably mounted in said pinion bore, an axially extending drilled and tapped portion at one end of said quill rod, an axially extending saw cut at said drilled and tapped end of said quill rod, an adjustment screw threaded into said drilled and tapped end of said quill rod, said adjustment screw having an enlarged chamfered head portion, means in said quill rod receiving a material to be woven, and

5

means operable to thread said adjustment screw into and out of said drilled and tapped portion of said quill rod, expanding said quill rod substantially diametrically into engagement with said pinion and thus holding said quill rod securely mounted thereon, when said adjustment screw is threaded into said drilled and tapped portion, and conversely said adjustment screw releasing the expanding force on said quill rod when said adjustment screw is threaded out of said drilled and tapped portion, whereby said quill rod returns to normal and releases the quill rod from the pinion.

10

6

6. In a device of the class described, a quill rod mounted in a pinion, said quill rod having an axially extending drilled and tapped portion, an axially extending saw cut through at least a portion of said drilled and tapped portion, means comprising an expanding adjustment screw threaded into said drilled and tapped portion, said last-mentioned means expanding said quill rod to engagement with said pinion whereby said quill rod and said pinion means are releasably secured against movement relative to each other.

CARL O. BRUESTLE.
